Primary Examiner — Garth Rademaker(74) *Attorney, Agent, or Firm* — Davis Wright Tremaine LLP(57) **CLAIM**

The ornamental design for a bottle opener, as shown and described.

DESCRIPTION

FIG. 1 is a perspective view of a bottle opener, showing our new design.

FIG. 2 is a top plan view thereof;

FIG. 3 is a bottom plan view thereof;

FIG. 4 is a rear elevation view thereof;

FIG. 5 is a front elevation view thereof;

FIG. 6 is a left side elevation view thereof, shown at an enlarged scale; and,

FIG. 7 is a right side elevation view thereof, shown at an enlarged scale.

The double dot-dashed broken lines show a corkscrew, a knife, a bottle cap opener, and interior gripping elements, none of which form a part of the claimed design.
